RECOIL PAD FOR FIREARMS

George L. Herter, Waseca, Minn.

Application July 25, 1957, Serial No. 47,081

Term of patent 14 years

(Cl. D30—1)

FIG. 1

FIG. 2

Fig. 1 is a view in side elevation of a recoil pad for firearms, showing my new design; and

Fig. 2 is a rear elevational view of the same.

The undisclosed side of the recoil pad is the same in appearances as the side shown.

I claim:

The ornamental design for a recoil pad for firearms, substantially as shown and described.
